UNITED STATES PATENT OFFICE.

KIERAN A. KELLY, OF NEW YORK, N. Y.

DESIGN FOR AN ARTICLE OF MANUFACTURE.

53,370.

Specification for Design.

Patented May 27, 1919.

Application filed December 14, 1918. Serial No. 266,820. Term of patent 3½ years.

To all whom it may concern:

Be it known that I, KIERAN A. KELLY, a citizen of the United States, and a resident of the city of New York, borough of Manhattan, in the county and State of New York, have invented a new, original, and ornamental Design for an Article of Manufacture, of which the following is a specification.

Reference is to be had to the accompanying drawing, in which the figure is a brooch or lace pin in accordance with the present design.

The design can be adapted to various forms of articles, such as emblems, lapel buttons, stickpins, and watch charms.

I claim:

The ornamental design for an article of manufacture as shown and described.

KIERAN A. KELLY.
